UNITED STATES PATENT OFFICE.

THOMAS BROZ, OF CALUMET, MICHIGAN.

MUSIC-LEAF TURNER.

1,288,822.

Specification of Letters Patent. Patented Dec. 24, 1918.

Application filed July 20, 1918. Serial No. 245,928.

To all whom it may concern:

Be it known that I, THOMAS BROZ, a citizen of the United States, residing at Calumet, in the county of Houghton and State 5 of Michigan, have invented new and useful Improvements in Music-Leaf Turners, of which the following is a specification.

This invention relates to new and useful improvements in music leaf turners and the 10 principal object of the invention is to provide means for turning the leaves of sheet music and is adapted to be used on pianos.

Other objects of the invention are to provide a number of leaf engaging members 15 carried by a plurality of sleeves, of a frame provided with means for rotating the sleeves, and of means for moving the frame.

Another object of the invention is to provide a device of this character which is 20 simple and durable in construction, reliable and efficient in operation and one which can be manufactured and placed upon the market at a minimum cost.

The invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the 35 several views, and in which:—

Figure 1 is a front view of the invention.

Fig. 2 is a like view with the music holding member removed.

Fig. 3 is a horizontal sectional view.

Fig. 4 is an enlarged view of the actuating means.

Fig. 5 is a longitudinal section through the sleeves.

Fig. 6 is an enlarged view of one of the 45 sleeves.

Fig. 7 is a detail view of one of the leaf engaging members.

Fig. 8 is a section through the music support showing the means for holding the 50 sheet music to the music support.

As shown in these views the device is placed in a small casing 1 and it consists of an actuating shaft 2 suitably supported at one end of the casing and adapted to be 55 driven by a large toothed wheel 3, suitably journaled in the lower part of the casing,

and engaging with a bevel gear 4 secured to said shaft. The toothed wheel is adapted to be rotated in either direction by a pair of operating members or levers 5, located 60 on the opposite sides of the wheel. Each of these levers has one end hinged to the casing and a spring 6 tends to hold said lever in its uppermost position. Each lever is provided with a spring controlled pawl 65 7 which engages the teeth of the wheel. These pawls are so arranged that when the levers are depressed the wheel will be rotated. These levers may be so arranged as to project from the casing so as to be operated by hand, or said levers may be suitably connected with foot pedals so that they may be operated by the foot.

The upper end of the shaft carries a pair of chain wheels 8, spaced apart and adapted 75 to engage a pair of chains 9. At the other end of the casing the chains pass over guide pulleys 10 and the ends of the chains are secured to a rectangular frame 11. In this manner when the shaft is rotated by the operating levers the chains will be caused to move the frame from one end of the casing to the other.

The frame has a plurality of horizontally extending wires 12 extending across the same 85 and spaced apart and these wires are connected together by short pieces of wire 13 arranged to be out of alinement with each other. If desired these short pieces may be formed by looping the horizontally extending 90 wires themselves.

These short pieces form engaging dogs, the purposes of which will be hereinafter fully described.

14 indicates a vertical shaft suitably journaled in the casing at a point substantially midway between the actuating shaft and the guide pulleys. The shaft is immediately in rear of the frame 11 and supports a plurality of sleeves 15 nested together on said shaft. 95 The sleeves are of varying diameters to fit one over the other and of different lengths so that the upper end of each sleeve will extend above the upper end of the surrounding sleeve. The upper end of each sleeve is 100 provided with a pair of fingers 16 extending at right angles and the fingers of each pair being spaced apart. Each pair of fingers is located between a pair of the horizontally extending wires and project a sufficient distance therebetween to engage the dogs 13 105 carried by the frame. In this manner when

the frame is moved the dogs coming in contact with the fingers will partially rotate the sleeves and the fingers are so arranged that when the frame moves in one direction it will rotate the sleeve approximately a half turn in one direction and when the frame is moved in the opposite direction it will rotate the sleeve back to its normal position.

10 A leaf engaging member 17 is suitably connected with the bottom of each sleeve. Each member is provided with a flexible outer end and has a pair of clamping jaws 18 secured thereto which are adapted to engage the leaves.

19 is the music support which is made of any desired shape and of any desired size. I prefer to hinge this support to the front of the case so that it may be swung outwardly to expose the interior of the casing. The support is provided with a pair of centrally arranged ears 20, each provided with a perforation to receive a bar 21 of wire or the like which is adapted to be placed over 25 the junction of the leaves to hold the sheet music in place.

In carrying out my invention I secure the sheet of music or the book on the support and then connect each pair of jaws carried 30 by the fingers 16 to each leaf. Then by operating the actuating levers the leaves may be turned in either direction.

It is thought from the foregoing description that the advantages and novel features 35 of my invention will be readily apparent.

I desire it to be understood that I may make changes in the construction and in the

combination and arrangement of the several parts, provided that such changes fall within the scope of the appended claims.

40

What I claim is:—

1. A device of the class described comprising an actuating shaft, means for operating the same, a reciprocating frame connected with the shaft, engaging members on 45 the frame arranged out of alinement with each other, a second shaft, a plurality of sleeves nested on said shaft, a pair of fingers carried by each sleeve and adapted to be engaged by said members and a leaf engaging member connected with each sleeve.

50

2. A device of the class described comprising an operating shaft, means for actuating the same, a pair of chain wheels on said shaft, a pair of guide pulleys, chains passing over said wheels and pulleys, a frame connected with said chains, horizontally extending wires on said frame, operating dogs carried by said wires, a second shaft, a plurality of sleeves nested on said shaft, fingers on said sleeves adapted to be engaged by said dogs and leaf engaging members carried by said sleeves.

55

3. A device of the class described comprising an operating shaft, a toothed wheel, a bevel wheel on the shaft engaging with said toothed wheel, a pair of operating levers, spring pawls carried thereby and engaging with the toothed wheel for turning the same in different directions, and leaf turning means operating by said shaft.

60

70 In testimony whereof I affix my signature.

THOMAS BROZ.
